PAPER ROLL SLOTTING MACHINE

Rudolph G. Birr, Lombard, Ill., assignor, by mesne assignments, to Steiner American Corporation, Salt Lake City, Utah, a corporation of Nevada

Filed June 5, 1957, Ser. No. 663,787

1 Claim. (Cl. 90—21)

This invention relates to paper working machinery and the art of paper converting, and more particularly to a highly improved machine for slotting the ends of paper rolls.

In the paper making art the use of high speed paper making machines has greatly increased the ability of the industry to produce bulk paper in great volume at reduced costs, but many problems remain in economically converting the large rolls of bulk paper to smaller rolls that can be used by the ultimate consumer. The problem is especially acute in such highly competitive fields, for example, as the production of absorbent paper toweling where the large bulk rolls of paper must not only be converted as cheaply as possible into small rolls, but where the ends of the small rolls in certain cases must further be provided with accurately arranged and accurately shaped slots that will permit the rolls ultimately to be properly received upon inexpensive wing-type roll support spindles in towel dispensing mechanisms.

One of the principal objects of the present invention is to provide a machine for inexpensively, rapidly and accurately slotting the corresponding ends of individual paper rolls, one after another, in such a way that the shape and configuration of the corresponding slots, and their relative dispositions in the ends of successive rolls, will be substantially identical, thus insuring that all of the individual rolls may be properly received and supported in suitable dispensing mechanisms designed to handle rolls having that particular configuration of slots. Another object of the invention is to provide a machine of the character just stated that may be entirely automatic in its operation, thereby reducing to a minimum the cost of forming the slots in the ends of the individual rolls. Yet another object of the invention is to provide a machine of the foregoing character having means by which the disposition of the slots, relative to the axes of the rolls in which they are cut, may be selectively varied.

The machine of the present invention employs one or more circular saws, or the equivalent, for cutting the slots in the paper rolls, and a further object of the invention is the provision of improved means for advancing the paper rolls through the machine and for moving the rolls endwise, one by one, into cutting contact with the saws. Yet another object of the invention is to provide in the machine means for accurately guiding and orienting the ends of the rolls with respect to the saw blades, and for firmly steadyng the rolls without tending to crush the same while the actual cutting is taking place, thereby insuring that the disposition of the slots in successive rolls will be identical for all practical purposes.

These and other objects and advantages of the present invention will be apparent from the following description of a preferred embodiment thereof, taken with the accompanying drawings, wherein:

Fig. 1 is an elevational view of one end of a paper roll slotting machine constructed in accordance with the invention, a portion of the view being shown in cross-section taken substantially along the line 1—1 in Fig. 2;

2

Fig. 2 is a vertical cross-section of the machine taken substantially along the line 2—2 in Fig. 1 and showing a paper roll therein in a predetermined position which it occupies prior to being moved axially into cutting contact with a pair of rotary saw blades, one of the saw blades being shown in a raised position and the other being shown in phantom in a lower position;

Fig. 3 is a cross-sectional view similar to Fig. 2, but showing the paper roll in the position that it occupies after it has been advanced into full cutting contact with the saw blades, the machine being shown in this view with its saw blades occupying co-axial lower positions later to be described;

Fig. 4 is a fragmentary top plan view of the right hand end portion of the machine, as viewed in Fig. 2, taken substantially along the line 4—4 in that figure, and again showing the roll of paper in the position which it occupies immediately before its advancement axially into cutting contact with the saw blades;

Fig. 5 is a similar view taken substantially along the line 5—5 in Fig. 3, showing the roll of paper in the position that it occupies after it has been advanced into cutting contact with the rotary saw blades;

Fig. 6 is a cross-sectional view taken substantially along the line 6—6 in Fig. 4 to show the details of the mounting of the saw blades and to show their relative offset positions when the machine is adjusted with the axis of one blade above that of the other;

Fig. 7 is an elevational view of one side of an indexing head and guide assembly for the paper roll, as viewed substantially along the line 7—7 in Fig. 6;

Fig. 8 is a fragmentary perspective view of one end of a paper roll showing one arrangement of slots that may be cut therein by the present machine, and showing a suitable spindle that may be employed for rotatably mounting that end of the roll in a dispensing device for the paper;

Fig. 9 is a similar view of an end of another roll of paper, illustrating an alternate arrangement of slots that may be cut in the roll by the present machine, and showing a spindle that may be employed for rotatably mounting that end of the roll; and

Fig. 10 is a fragmentary perspective view of the end of still another roll, showing a further variation in the disposition of slots that may be cut by the present machine in the roll, and showing a spindle that may be employed in rotatably mounting that end of the roll in a paper dispensing mechanism.

The present embodiment of the machine comprises a base frame having four upstanding legs 11, 12, 13 and 14 that may rest upon a floor or other supporting surface. These legs may be formed of angle iron and are preferably joined at their upper ends, as by welding or the like, by cross members 15, 16, 17 and 18, the latter of which, like the legs, may comprise lengths of angle iron. The cross members form a horizontally disposed rectangular frame upon the upper ends of the legs and this table-like frame supports the remaining elements of the machine.

Referring now to Figs. 1, 2 and 3, it will be seen that a base plate 19 is fixed upon the upper surface of the base frame. Secured to the underside of the base plate, as by machine screws 20, there is a pair of forwardly projecting parallel frame members 21 and 22 that extend through suitably shaped openings 23 and 24 cut in the forward horizontally extending cross member 15. The outermost ends of the frame members 21 and 22 are tied together by a cross-block 24 having a bearing 26 therein which rotatably journals the outer end of a shaft 27. The inner end of this shaft is similarly journaled in a bearing 28 provided in a cross-block 29 which extends laterally between, and is mounted upon, the forwardly extending frame members 21 and 22 adjacent their inner

ends, a slot 30 being provided in the base plate 19, as illustrated in Fig. 6, in order to accommodate the bearing 28 and its housing. The shaft 27 has fixed thereon a paper roll receiving holder and impeller assembly designated generally by the numeral 30. This assembly comprises two axially spaced apart spiders 31 and 32 that are fixed upon the shaft and joined by a plurality of radially extending vanes 33 that are equiangularly arranged, the peripheral portion of each of the spiders 31 and 32 being concave in shape between each of the vanes, as best seen at 34 in Fig. 1. As best seen in Figs. 1 and 4, the base plate 19 may be cut out, as at 19a, and the forward cross member 15 of the base frame may be interrupted as at 15a, in order that these elements will not interfere with rotary movement of the roll receiving holder and impeller assembly 30.

The shaft 27 with the impeller assembly thereon is arranged to be intermittently rotated. An electric motor 35 (Fig. 1) is provided for this purpose, the motor being fixed upon a platform 36 mounted upon the upper ends of a plurality of posts 37 and 38 that are respectively supported and fixed at their lower ends upon the forwardly directed frame members 21 and 22. The drive shaft 39 of the motor 35 is connected to one side of a speed reducing unit 40 through a flexible coupling 41, and the opposite side of the speed reducing unit is provided with a drive shaft 42 having a pulley 43 thereon that drives a larger pulley 44 by means of a belt 45. The larger pulley 44 is fixed upon the outer end of a shaft 46 that is journaled in a pair of bearing blocks 47 mounted upon the underside of the platform 36. The opposite end of the shaft 46 has a crank arm 48 fixed thereon, as by a key 49 (Fig. 2). The outer end of the crank arm has a pin 50 thereon that is rotatably received in a collar 51 that has the upper end of a connecting link 52 pivotally secured thereto. The lower end of the link is pivotally fastened to another collar 53 that is rotatably journaled upon the shank of a pin 54 that extends through the legs 55 and 56 of a forked arm 57 that is rotatably journaled upon the shaft 27 inwardly of the bearing 26. The arrangement is such that when the motor 35 drives the shaft 46 through the medium of the speed reducing unit 40 and the pulleys 43 and 44, the crank arm 48 is rotated and the connecting link 52 is thus reciprocated up and down. Vertical reciprocation of this link causes the arm 57 to be freely pivoted in reciprocating angular motion upon the shaft 27, it being understood that the arm 57 is free to rotate about the latter shaft. The reciprocating angular movement of the arm 57 is transmitted to the shaft 27, and thus to the impeller 30, by means of a pawl and ratchet assembly. The pawl 58 of this assembly is pivotally mounted upon the pin 54 and is arranged, as best illustrated in Fig. 1, to cooperate with a ratchet 59 that is fixed upon the shaft 27 immediately inwardly of the bearing 26. Thus, upon each revolution of the shaft 46 the pawl 58, which is spring-biased by a spring 58b toward the ratchet, is retracted or lowered sufficiently to cause its outer end 58a to engage one of the ratchet faces 59a of the ratchet 59. During the latter portion of each revolution of the shaft 46, the pawl 58 is returned to its original position, thereby advancing the ratchet and causing the shaft 27 and the impeller assembly 30 to be rotated through a portion of a revolution. In the embodiment of the invention illustrated in the drawings, the impeller assembly 30 is provided with five vanes 33 and the ratchet 59 is provided with an equal number of ratchet faces 59a, so that during the latter half of each revolution of the shaft 46 the shaft 27 and the impeller assembly 30 thereon are rotatably advanced substantially 72 degrees. During this advancing movement, one roll of paper 60, occupying the position on the impeller assembly illustrated in Fig. 1, is carried counterclockwise with the impeller and rolls therefrom onto a discharge table 61 which may direct that roll to a packing station, not illustrated. During the discharge of the roll 60 from the impeller assembly,

a new roll 62 will be picked up by the succeeding set of vanes 33 of the impeller assembly and will be carried upwardly in a counterclockwise direction thereon to the predetermined position previously occupied by the roll 60, the new roll 62 and succeeding rolls being fed successively to the impeller by gravity by means of an inclined chute 63 that may be supported by a bracket 64 upon the base plate 19 of the frame of the present machine.

10 The shaft 46 inwardly of the crank arm 48 has a large cam 65 fixed thereon which rotates with the shaft in the direction of the arrow 66 (Fig. 2), the platform 36 being cut out, as at 36a, in order to avoid interference with the rotation of the cam and the crank arm 48. The cam 65 has a large cam face 67 and a joining shorter cam face 68 formed thereon which cooperate with a cam follower roller 69 provided at one end of a push rod 70 of rectangular cross section that is slidably mounted in a block 71 fixed upon the underside of the platform 36. 15 The forward end portion 70a of the push rod 70 may be cylindrical in shape and is slidably mounted in another block 72 mounted on the underside of the platform 36 and provided with a suitable bearing 72a. The forward extremity of the push rod has a downwardly extending 20 retraction plate 73 fixed thereon as by a collar 74 and a nut 75 received upon threads formed on the outermost end of the cylindrical portion 70a of the push rod, the retraction plate being connected by means of a tie rod 76 to a downwardly extending advancing plate 77 carried 25 by the rectangular portion of the push rod 70. The tie rod 76 slidably extends through a suitable opening 72b in the block 72 and serves not only to tie the two plates 73 and 77 together, but also to prevent any tendency for the retracting plate 73 to rotate about the axis of the 30 cylindrical portion 70a of the push rod 70.

The downwardly extending retraction plate 73 and the advancing plate 77 are disposed directly above the axis of the impeller shaft 27 and are spaced apart a distance somewhat greater than the length of the paper 35 rolls that are fed to the machine, the disposition of the plates 73 and 77 being such that when the push rod 70 is reciprocated, the plates will engage the opposite ends of any roll in the position of the roll 60 and will cause that roll to slide in reciprocating axial motion on the impeller assembly 30. Thus, referring to Figs. 1, 2 and 3, it will be observed that during the first part of a revolution of the cam shaft 46, the push rod 70 with the plates 73 and 77 thereon are moved by the cam 65 to the right (as viewed in Figs. 2 and 3), the plate 77 contacting one end of the roll 60 and advancing that roll in the same direction. During this movement the roll 60 slides across the concave surfaces 34 of the two spiders 31 and 32 of the impeller assembly and also along the two supporting vanes 33, the roll thereby being advanced from the position thereof shown in Fig. 2 to the position 40 shown in Fig. 3. The forward end 60b of the roll 60 during this advancing movement is brought into cutting or slotting contact with a pair of circular saw blades 78 and 79 which will be described in greater detail hereinafter. Having been advanced to the position shown 45 in Fig. 3 and having been cut by the saw blades 78 and 79 to form a pair of slots in the end of the roll, the roll 60 is immediately returned to its original position shown in Fig. 2. This returning movement is accomplished by the fact that the cam follower 69 leaves the cam face 67 and thereupon follows the shorter cam face 68, thereby permitting a relatively strong tension spring 80 to return the push rod 70 from the position illustrated in Fig. 3 to its original position shown in Fig. 2. During this returning movement of the push rod 70, the retraction 50 plate 73 contacts the end 60a of the roll 60 and slides the roll on the impeller assembly 30 back to its original position thereon. By the time this movement has been accomplished, the crank arm 48 will have reached its lowermost position and will begin its upward travel, thereby causing the pawl 58 to engage one of the ratchet 55 faces 59a.

surfaces 59a of the ratchet 59. During the remaining portion of the rotation of the cam shaft 46, the impeller 30 is rotatably advanced in the direction of the arrow 81 in Fig. 1, thereby discharging the roll 60 from the impeller and onto the table 61, and causing the fresh roll 62 to be picked up by the impeller and raised to the predetermined position previously occupied by the roll 60. The tension spring 80, it will be observed, may be anchored at one of its ends to a pin 81 that is fixed to the block 71 and may be fastened at its opposite end to a pin 82 that is secured to the retraction plate 73, it being understood that the spring 80 causes the cam follower 69 to remain in constant contact with the cam faces of the cam 65.

As previously indicated, fresh rolls of paper represented by the roll 62 in the drawings, are fed successively by gravity toward the impeller assembly 30 in the inclined chute 63. It will be observed, however, that the fresh rolls are admitted to the impeller only at the proper time to be raised by the impeller to the predetermined position occupied by the roll 60 in Fig. 1. To this end a stop arm 83 is provided, one end of the arm being pivotally mounted at 84 upon the underside of the platform 36. The underside of the arm 83 is provided with a bracket 85 which carries a roller 86 adapted to ride upon a cam surface 87 that is fixed upon the side of the push rod 70, the cam surface being so located and so shaped that during the returning movement of the push rod from its advanced position (Fig. 3) to its retracted position (Fig. 2), the roller 86 and the arm 83 are lifted to the broken line position thereof shown in Fig. 2 to permit one of the fresh rolls, represented by the roll 62, to pass under the arm and roll into contact with the impeller assembly 30. The outer end of the arm 83 is preferably provided with a roller 88. At all times when the push rod 70 is out of its retracted position (Fig. 2), the arm 83 is retained by gravity in the position shown in Fig. 1 by the solid lines, in which position the roller 88 is in contact with the leading one of the fresh rolls of paper and acts as a stop to prevent that roll of paper and subsequent rolls from rolling downwardly into contact with the impeller assembly.

The saw blade 78, previously mentioned is mounted upon the outer end of a spindle 90 that is rotatably journaled in a bearing block 91 and driven by a pulley 92 by means of a belt 93 and another pulley 94 carried upon the shaft of an electric motor 95. The bearing block 91 forms a part of a casting, designated generally by the numeral 96, which has an arm 97 integrally formed thereon and projecting diagonally upwardly. A motor mounting plate 98 is secured by a pin upon the upper end of the arm and the plate 98, in turn, has the motor 95 secured thereto in any suitable fashion. The rotary saw blade 79 is similarly secured upon the outer end of a spindle 100 that is journaled in a bearing block 101 that is a part of a casting 102 substantially identical to the casting 96. The casting 102 has an arm 103 integrally formed thereon and extending diagonally upwardly (Fig. 2). At the upper end of the arm a motor mounting plate 104 is mounted thereon, as by a pin 105, and the plate 104 carries an electric motor 106. This motor has a pulley 107 on its shaft, and the pulley 107 drives a similar pulley 108 by means of a belt 109, the pulley 108 being affixed upon the outer end of the spindle 100 so that the motor 106 drives the saw blade 79.

As perhaps best seen in Figs. 2 and 3 the casting 102 is mounted by means of a heavy bolt 110 upon a block 111 that is fixed in any suitable manner upon a forwardly projecting arm 112 of an L-shaped bracket 113. The other leg 114 of this L-shaped bracket extends upwardly and is pivotally mounted by means of a pin 115 between a pair of ears 116 formed upon an upstanding block 117 that is fixed upon the upper surface of the base plate 19 adjacent its rear edge. The bracket 113 is thus arranged

to be pivotally raised or lowered, as illustrated in Figs. 2 and 3 respectively, in order to raise or lower the position of the axis of the rotary saw blade 79. In its lowered position, the leg 112 of the L-shaped bracket 113 rests flat against the upper surface of the base plate 19 (Fig. 3) and may be secured in that position by a bolt 118 which may be threaded into a suitable opening in the base plate. In its raised position, on the other hand, a pair of blocks 119 are preferably placed under the outer extremity of the leg 112 of the bracket on opposite sides of the bolt 118 to support the bracket in its elevated position, the bolt 118 passing downwardly between the two blocks 119 and being threaded into the same opening in the base plate 19 that is used when the L-shaped bracket 113 is in its lowered position.

The mounting of the casting 96, which supports the saw blade 78 and its spindle 90, is identical to the mounting of the casting 102 just described. The casting 96 is secured by means of a bolt 120 upon a block 121 that is fixed upon a forwardly projecting leg 122 of another L-shaped bracket 123 that is identical to the corresponding bracket 113 and which is pivotally mounted in the same fashion as the latter bracket, the L-shaped bracket 123 thus being capable of being pivotally raised and lowered in order to accomplish selective raising and lowering of the axis of the saw blade 78. The L-shaped bracket 123 in Fig. 6 is shown in its elevated position with a pair of blocks 124 placed under the forward end of its leg 122, the bracket 123 being secured in this position by means of a bolt 125 that is passed downwardly through a suitable opening in the leg 122 and is threaded into the base plate 19. By removing the blocks 124, the under-surface of the bracket 123 may be caused to lie flush upon the upper surface of the base plate 19 and the bracket may be secured in that position by the bolt 125, thus lowering the circular saw blade 78 to a position coaxial with the position of the circular saw blade 79 in Fig. 6.

From the foregoing it will be understood that the mounting of the two saw blades 78 and 79 is such that they may be respectively and selectively raised and lowered with respect to the base plate 19 of the frame of the present machine, and thus with respect to the axis of the paper roll that is supported by the impeller assembly 30 and moved axially toward and away from the saw blades for slotting.

Figs. 8, 9 and 10 show the corresponding ends of three representative paper rolls 126, 127 and 128 that have been slotted by the blades 78 and 79 of the present machine when the blades are in different selected positions. The roll 126 (Fig. 8) has a pair of slots 129 and 130 that have been cut therein when the blade 78 is in its raised position and when the blade 79 is in its lowered position, as illustrated in Fig. 6, it being understood that the blade 78 will have cut the slot 130 and the blade 79 will have cut the slot 129. Inasmuch as the blades are spaced apart, the two slots 129 and 130 are offset with respect to the axis of the roll 126 and their radial centers are also offset. When slotting of the arrangement shown in Fig. 8 is used, the end of the roll 126 may be pivotally supported in a suitable dispensing cabinet or the like provided with a very inexpensive, rotatably mounted wing-type spindle 131 comprising a flat plate 132 having ears 133 and 134 formed thereon corresponding or complementary to the shape and disposition of the slots 129 and 130, respectively. When the roll 126 is mounted upon the spindle 131, the ear 133 fits into the slot 129 so that the curved outer edge 133a of the ear engages the arcuate bottom 129a of the slot 129. Similarly, the curved outer edge 134a of the ear 134 will engage the arcuate bottom 130a of the slot 130 and, thus, will support the illustrated end of the roll 126 for rotation about the axis of pivotatation of the spindle 131.

The arrangement of the slots in the representative roll 127, shown in Fig. 9, is an arrangement that may be

cut in the end of the roll when the saw blade 78 is in its lowered position and when the saw blade 79 is in its raised position. Thus, the saw blade 78 will cut an arcuate slot 135 in the end of the roll and the other saw blade will cut a slot 136 therein, each slot being offset with respect to the axis of the roll and with respect to each other. When a roll is slotted in this manner, the slotted end thereof may be rotatably supported on a rotatably mounted spindle 137 having an ear 139 formed thereon, the outer curved edge 138a thereof being complementary to the shape of the arcuate bottom 135a of the slot 135. The spindle 137 also has another ear 139 formed thereon adapted to be received within the slot 136, the arcuate outer surface 139a of the ear 139 being adapted to come into supporting contact with the arcuate bottom 136a of the slot 136.

When a symmetrical configuration of slots is used such as those illustrated in Figs. 8 and 9, it will be observed that the respective cores 140 and 141 of the rolls in fact play no part in the actual support of the ends of the rolls, the entire vertical support being provided by the engagement of the ears of the spindles with the arcuately curved slots, thereby making it unnecessary for the rolls to be provided with cores except as may be needed during the original winding or formation of the rolls. Furthermore, it will be seen that the wing-type spindles 131 and 137, in addition to supporting the rolls of paper, will also serve as a means for rotatably driving the rolls when such drive is desired or, conversely, the withdrawal of paper from the rolls will drive the spindles for any purpose that may be desired.

Fig. 10 shows a roll 28 having an end that has been slotted when both of the rotary saw blades 78 and 79 have been co-axially arranged, that is, when both of the blades have been arranged in their lower positions or in their upper positions. Assuming that the blades have both been arranged in their lower positions during the slotting, the blade 78 will have formed a slot 142 in the end of the roll and the other blade will have formed a slot 143 therein. When this arrangement of slots is employed, a rotary mounted spindle 144 may be employed for rotatably supporting the slotted end of the roll in a suitable dispensing cabinet. This spindle is provided with a pair of ears 145 and 146 that are respectively adapted to be received in the slots 143 and 142, with the arcuate outer edges of the ears engaging the arcuate bottoms of the slots. The spindle 144 may also be provided with a lug 147 that engages the inner surface of a core 148 of the roll, thereby providing complete support for the roll during the dispensing of paper therefrom.

In order to insure that each paper roll is properly oriented or centered with respect to the saw blades 78 and 79 during the advancement of the roll toward the saw blades and properly steadied during the slotting thereof, an orienting head or pilot is provided which receives and guides the roll axially immediately before and during the slotting operation. The orienting head or pilot assembly includes an upstanding bracket 150 secured upon the base plate 19 to the rear of the saw blades by means of one or more bolts 151. The upwardly extending bracket has a cylindrical opening 152 (Fig. 7) therein which slidably receives a cylindrical plug 153. On the forward end of this plug there is formed a vertically extending plate 154 that is intimately disposed between the two saw blades 78 and 79, but slightly spaced therefrom, as perhaps best seen in Fig. 6, and on the forward edge of the plate 154 there is formed a cone-shaped orienting head or pilot 155. It will be observed that the cylindrical base portion 155a of this cone-shaped orienting head has a diameter only slightly less than the inner diameter of the core or axial opening in the rolls, and the base is of a size such that it, in effect, intersects the planes of the two saw blades as shown in Fig. 6. That is, the saw blades, in effect, are located in recesses behind the orient-

ing head or pilot 155. The orienting head assembly, which includes the plate 154 and the plug 153, may be held in fixed position with respect to the bracket 150 by means of a set screw 156 which may be threaded downwardly through the top of the bracket 150 and into engagement with the cylindrical plug 153 of the orienting head. It will be observed that the arrangement of the orienting head is such that it does not interfere with the saw blades 78 and 79 or with their selective adjustment between their upper and lower positions. In order to provide accurate positioning of the plate 154 of the indexing head with respect to the planes of the saws, however, a leader pin 157 (Fig. 7) may be provided on the rear of the plate 154 below the plug 153, this leader pin being adapted to be slidably received in an opening 158 provided in the bracket 150.

A slidably mounted spring-loaded shield or cap 159 is mounted on the indexing head bracket 150 in such a was as to cover the saw blades 78 and 79 at all times 20 when the blades are not contacted by a paper roll, thereby making the machine safer for workmen who may be around the machine in the course of their duties. The shield comprises a top panel 160 which rests on the flat top surface of the bracket 150 and also includes side 25 panels 161 and 162 that are integrally joined by a rear panel 163, the side and rear panels being fabricated, if desired, from a single sheet of metal that may be welded or otherwise secured to downwardly turned flanges 160a formed on the lateral edges of the top panel 160. The 30 space between the side panels 161 and 162 is such that the guard assembly is in the nature of a sheet metal cap resting upon the top of the bracket 150 and capable of 35 rearward sliding movement thereon to expose the blades 78 and 79, and returning forward sliding movement to cover the blades. In Fig. 7, the guard assembly is shown in its forward, blade covering position. The rear panel 163 of the guard assembly is provided with a pair of 40 openings that are slidably received upon a pair of studs 164 that are threaded into the rear side of the bracket 150. Each of the studs 164 has a compression spring 165 thereon, one end of the spring bearing against the head of the stud and bearing at its other end against the back surface of the rear panel 163. Thus, it will be 45 understood that the guard assembly 159 is biased by the compression springs 165 toward the blade covering position illustrated in Fig. 7 and in Fig. 4. The side panels 161 and 162 are provided on their forward edges with 50 turned tabs 166 that are adapted to be contacted by the forward end of each roll of paper as that roll is advanced toward the saw blades by the push rod 70 and its advancing plate 77. Movement of each roll toward the saw blades thus pushes the guard assembly rearwardly so as 55 automatically to expose the saw blades as the paper roll advances into contact with the blades, the force of the springs 165 automatically returning the guard assembly to its original blade covering position as the roll of paper 60 is retracted from the saw blades after the slotting has been accomplished. The compression of the springs 165, it will be observed also assists the tension spring 80 and the roll retracting arm 73 of the push rod 70, in disengaging each roll of paper from the saw blades 78 and 79 after the slotting of the roll has been accomplished.

In the present machine, the rotary saw blades 78 and 79 are spaced apart on parallel axes that are normal 65 to the axis of the drive shaft 27 and, thus, normal to the axis of the roll of paper that is in position on the impeller 30 and ready to be slotted. The space between the saw blades is less than the diameter of the axial opening that extends through each roll from end to end, and the diameter of each blade is such that parallel offset slots may 70 be cut in the ends of the rolls without causing either of the slots to extend from one side to the other of the axial opening in the roll.

From the foregoing description it will be appreciated 75 that the rolls of paper to be slotted are intermittently and

successively advanced along a path through the present machine entirely automatically, each roll successively being picked up by the impeller assembly 30 and moved thereby to a predetermined position wherein the projected axis of the positioned roll is substantially co-axial with the indexing head or pilot 155, and intermediate and equidistant from the planes of the two saw blades. This controlled movement of the impeller is automatically accomplished by the ratchet 59 and the pawl 58 previously described, and a brake may be employed on the shaft 27 of the impeller to prevent over-run. To this end, the outermost end of the shaft has a brake drum 170 fixed thereon (Fig. 1), which is engaged on opposite sides by a pair of upstanding brake shoes 171, the lower ends of which may be pivotally mounted upon a stud 172 threaded into the cross-block 25. The upper ends of the brake shoes may be adjustably secured together by a bolt 173 in a well known manner such that adjustment of the bolt 173 will selectively vary the braking action of the shoes upon the drum 170. This simple and inexpensive braking arrangement prevents over-run of the impeller assembly 30 and helps insure that the positioned roll of paper on the impeller will be in proper alignment with the pilot 155 and ready to be moved axially from its predetermined position on the impeller toward the saw blades by the reciprocating push rod and its advancing and retracting plates 77 and 73.

As explained above, when the impeller 30 has deposited or carried the paper roll thereon to its predetermined position in axial alignment with the pilot 155, the reciprocating push rod 70 and the plate 77 thereon slides the roll axially on the impeller toward the saw blades for slotting. The axial opening of the roll is slidably received, during this movement, upon the pilot 155 which accurately orients the roll with respect to the blades and guides and steadies the end of the roll during the actual cutting of the slots therein, thus insuring that the disposition of the slots in successive rolls will be identical. This guiding and supporting function of the pilot 155 is accomplished without any tendency whatever for the roll to be crushed, due to the fact that the supporting contact with the roll is made by the pilot at the center of the roll rather than upon the peripheral surface of the roll. The absence of crushing of the roll contributes to the accuracy and identity of the disposition of the slots as between successive rolls. When the slotting has been accomplished, the roll is automatically withdrawn from the saw blades and from the pilot by the returning reciprocation of the push rod 70, thereby returning the newly slotted roll to its original location on the impeller 30 and to the original path of the roll through the machine, whereupon a further rotation of the impeller will take place to discharge the roll from the machine and to pick up the next succeeding roll for slotting, as previously explained.

The foregoing description of a preferred embodiment of the present invention has been given for clearness of understanding only, and no unnecessary limitations are intended thereby, for it will be apparent to those skilled in the art that numerous variations, changes and modifications may be made in the machine without departing from the true spirit and scope of the appended claim which defines the invention.

I claim:

10 A machine for forming slots in the end of a substantially cylindrical roll of paper having an opening therein extending longitudinally therethrough, comprising a base, first mounting means on said base and adjustable vertically with respect thereto, a first saw blade rotatably mounted upon said first mounting means and having a diameter less than that of the roll, second mounting means on said base and adjustable vertically with respect thereto, a second saw blade rotatably mounted upon said second mounting means and having a diameter less than that of the roll, said saw blades being rotatable in planes substantially parallel to each other spaced apart a distance less than the diameter of the openings in the roll and being individually and independently adjustable with respect to said base and each other, power means for rotating said saw blades, means for moving a roll in a direction substantially parallel to the longitudinal axis thereof and parallel to the planes of rotation of said saw blades with the opening in the roll in general alignment with said saw blades, whereby to cut a pair of spaced apart slots 30 in the end of the roll disposed toward said saw blades with the slots extending outwardly from the opening through the roll, a movable guard mounted on said base and shiftable between a first position to cover the saw blades and a second position exposing said saw blades, means 35 biasing said guard toward said first position, and means on said guard adapted to engage the adjacent end of the roll to urge said guard to said second position as the roll is moved toward said saw blades.
